ATTORNEY.

UNITED STATES PATENT OFFICE.

ANNIE BOWMAN, OF LOS ANGELES, CALIFORNIA.

FACE-POWDER BOX.

Application filed March 12, 1924. Serial No. 698,649.

To all whom it may concern:

Be it known that I, ANNIE BOWMAN, a citizen of the United States, residing at the city of Los Angeles, county of Los Angeles, 5 State of California, have invented new and useful Improvements in Face-Powder Boxes, of which the following is a specification.

Heretofore there has been no means provided in a face powder box for conveniently 10 ridding the face puff of surplus powder without wasting it and soiling the dresser on which the box is usually kept. It is the object of my invention to provide a suitable device, illustrated as a tray, that is removably held in the top of the lower member of 15 the box by means of which the surplus powder which is usually taken up by the puff may be detached therefrom and returned to the bulk of powder in the box.

20 In the drawings forming a part of this application:

Fig. 1 is a top plan of a powder box equipped with my device, parts being broken away for illustration;

25 Fig. 2 is a section on the line 2—2 of Fig. 1;

Fig. 3 is a side elevation of the powder remover tray detached from the box.

In the drawings, 5 is the bottom or receptacle member of a face powder box of 30 any approved construction. The box illustrated being a pyroxyline box. 6 is the cover and 7 is the face puff, all of usual construction. In the top of receptacle 5, I 35 place the powder remover 8 which is preferably made from pyroxyline and is in shape a shallow tray with vertical side walls 9 having a ledge 10 projecting outwardly to extend beyond the top of member 5 and not 40 beyond the edge of cover 6. Remover 8 is preferably deep enough to conveniently hold puff 7 when not in use. The bottom 11 of the remover has perforations 12 so that

when the puff is rubbed thereon or shaken thereover the surplus powder will be detached therefrom and fall through the perforations into member 5. When not in use tray 8 holds puff 7 and is covered by the top 45 6. When it is desired to powder the face or neck or arms, cover 6 is removed and puff 50 7 is taken out of tray 8. The tray is then lifted out and the puff inserted into contact with the powder in member 5 and then removed therefrom and tray 8 returned into member 5. Puff 7 may then be shaken over 55 tray 8 so as to permit the surplus powder on the puff to fall into the tray or the puff may be rubbed on the tray to detach the surplus powder therefrom or to more equally distribute it thereon. By this means all 60 surplus powder is retained in member 5 and is prevented from soiling the clothes or the dresser as it now commonly done.

While I have illustrated the powder remover as a tray made from pyroxyline it 65 will be understood that it may be of any other material and of any suitable shape. The perforations in the bottom of the tray could be omitted but the tray is better with 70 perforations.

Having described my invention, I claim:

A face powder box for dressers comprising 75 a receptacle adapted to hold powder and a tray; a tray removably mounted in the top of said receptacle, said tray having a perforated bottom; and a cover for said tray, the vertical distance between the center of the cover and the bottom of the tray when the cover is positioned thereon being equal to the thickness of the powder puff adapted 80 for use therewith.

In witness that I claim the foregoing I have hereunto subscribed my name this 4th day of March 1924.

ANNIE BOWMAN.
